SUBGRADE PLANER

Nathan B. Bederman and Norman M. Jones, Chicago, Ill., assignors to Arcole Midwest Corporation, Skokie, Ill., a corporation of Illinois

Filed Jan. 20, 1955, Ser. No. 482,988

8 Claims. (Cl. 37—108)

The present invention relates to self-propelled machines for accurately preparing a filled sub-grade over which a pavement of concrete or other material is to be placed.

In most grading machines of the general class to which this relates road forms are used consisting usually of accurately placed and secured rail members which serve the purpose as forms for containing the subsequently applied paving material and which are utilized as wheel rails over which this and other processing machinery is rolled. Having to utilize road forms in this manner involves considerable expense and cost factors in addition to placement such as cleansing, oiling and maintenance between jobs.

It is a primary object of the present invention accordingly to devise a machine which will perform an accurate fine grading or planing operation without requiring the use of such forms in order to avail of the several economies which inure.

In order to fulfill the close tolerance conditions which are customary under highway and road building contracts the utilization of an alternative mode of operation necessarily requires an advance preparation of the side strips which flank a tentative roadway and this consists in leveling and stabilizing the granular fill in order to render travel over these side strips smooth and regular. Such preparatory operations of the side strips are also prerequisite to the use of forms.

It is accordingly another object of the present invention to devise a machine which may be supported on but partially prepared road strips which have undergone a rough scraping and gravel smoothing operation but not a rolling operation, and to perform thereafter a fill grading operation.

Another object of the present invention includes the provision of a machine of the class described which admits of a considerable degree of adjustment or enlargement to take care of variations in road widths.

Still another object of the present invention is to devise a machine of this class which lends itself notably to significant or partial dismantling so that it may be transported by rail or otherwise, handily and speedily to remote destinations.

Still another object of the present invention is to devise such a machine in which the framework is inherently yieldable to certain types of distortion strains which are unavoidable upon encounter with curbstones or other obstacles.

The foregoing and other objects and features of this invention are such as will become more evident during the course of the following detailed description of structure and operation as well as from the claims which follow hereinafter, taken in conjunction with the accompanying drawings. In both the drawings and description similar reference numerals designate corresponding parts throughout.

Figure 1 is a front elevational view, with minor portions broken away for compactness, of a sub-grade planer having embodied therein various features of the present invention.

2

Fig. 2 is a plan view thereof with certain minor portions broken away to reveal underlying details.

Fig. 3 is a side elevational view on a slightly enlarged scale of the apparatus disclosed in Figs. 1 and 2.

Fig. 4 is a fragmentary sectional view on an enlarged scale taken approximately on line 4—4 of Fig. 2 featuring the structural details surrounding the conveyor and planer blade.

Fig. 5 is a rear elevational view of the apparatus shown in Figs. 1 and 2.

Fig. 6 is an enlarged fragmentary detail rear elevational view of the coupling bracket and cushion mount characteristic of the trailing tamp mechanism.

Fig. 7 is a plan view of the structural detail illustrated in Fig. 6.

Fig. 8 is a transverse sectional view on an enlarged scale taken approximately on line 8—8 of Fig. 2.

Fig. 9 is a sectional view similar to Fig. 8 taken approximately on line 9—9 of Fig. 2.

Fig. 10 is a partial sectional view on an enlarged scale taken approximately on line 10—10 of Fig. 3.

Fig. 11 is a fragmentary side elevational view as indicated by line 11—11 on Fig. 2, and

Fig. 12 is a detailed perspective view with intermediate portions broken away of the scraper blade and its related fixture apparatus.

Referring now more particularly to the drawings, the reference numeral 21, Figs. 1-3, designates a principal transverse channel beam which is long enough to span a roadway and its ends extend through the supporting frame structures within the encompassment of the tractor treads 22 and 23, Fig. 5. Channel beam 21 is secured to the top of each pair of channel beam frame members 24 in tractor tread assembly 22, and 25 in tractor tread assembly 23, being therat bolted after the manner indicated at 26, Fig. 8. The subframe members 24 or 25 are pairs of spaced channel beams in the manner shown in Fig. 10 with their channel flanges facing outward. Within the spacing between each said pair of members and at each end of these assemblies there is provided front and rear journal blocks as at 28 and 27, Figs. 3 and 8, for supporting the front and rear sprocket shafts 29 and 31 respectively.

At the front, the journal shafts 29 support idler sprockets 32, while at the rear the shafts 31 support drive sprockets 33. Moreover, the shafts 31, one for each side frame, extend inwardly as best observed in Fig. 2, whereat they are additionally journaled as at 34 in blocks that rest upon extension brackets mounted on the principal beam 21.

The foregoing described arrangement has been purposefully designed so that the principal channel beam 21 can be variably secured to the subframe member pairs 24 and 25 to allow greater or smaller width variation in accordance with road beds which are constructed on 20, 22, or 24 foot width standards. During the course of the ensuing description it will be noted how other of the frame detail structure and driving mechanism admits of being dismantled and reassembled consistent with this plan of adjustment.

Nearer the front of the machine, by which is meant the lower portion as viewed in Fig. 2, there will be observed another transversely extending beam member 36, see also Fig. 4, which in this case is a wide beam channel disposed with its flanges extended vertically and lying across the subframe beams 24 and 25. This structural element is located significantly to the rear of the front idler sprockets 32 as best portrayed in Figs. 3 and 4. As evident from Figs. 1 and 2, channel beam 36 serves as a receptacle into which the granular material accumulations, when in excess of a predetermined quantity, are designed to spill over and be carried beyond

the range of the side strips 37, Fig. 1, traversed by the tractor treads.

Channel member 36 supports at its extremities the platforms 38, Fig. 2, on which are mounted journal brackets 39 and 41 for the shafts 42 which carry power-driven sprockets 43 and 44, Figs. 1 and 10. Around these sprockets 43 and 44 there is trained an endless belt link chain 45 which is prevented from drooping excessively at its upper flight by the provision of a series of support rollers 46 that are idly journaled in individual transverse shafts 47 sustained by vertical structure posts 48.

The lowermost flight of the endless chain belt 45, best viewed in Fig. 10, requires no such support because it is prevented from drooping by the engagement between sweep paddles 49, Fig. 4, riveted to the chain link brackets 51 carried by certain intervallic ones of the links, and the receptacle surface of channel 36.

Each of the shafts 42 of sprockets 43 and 44 is individually driven through a gear reduction unit 52 or 53 which imparts a characteristic direction of motion thereto. Reduction unit 52 is driven by a system of shafts 54 and universal joint connectors 55 from a transmission unit disposed beneath the platform 56, Fig. 2, as is also transmission unit 53 so driven over a system of shafts 57 and universal joints 58. By replacing the shaft lengths 54 with others of suitable size adjustment is made compatibly with any of several standard roadway widths.

By means of the control lever 59, Fig. 2, it is made possible for but one and only one of these power trains to be effective at a time. In this way the sweeping action of the conveyor belt 45 is reversible and may be made to discharge the granular accumulations in channel trough 36 either to the right or to the left of the roadway, as is expedient.

The rear sprockets 33, Fig. 8, mounted on shafts 31 impart driving power to the tractor treads 22 and 23. This power is obtained in each case from an individual drive chain 61, Figs. 2 and 8, which meshes with a driven sprocket 62 secured to each of the shafts 31 as well as with a driving sprocket 64 which is carried by the driving end shafts of the gear reduction units 65 and 66 appropriately supported on extensions from the principal frame beam 21. The aforescribed gear reduction units 65 and 66 are powered on the one hand by a system of shafts 67 and universal joints 68 and on the other hand by a system of shafts 69 and universal joints 71 from a differential transmission generally designated 72. Each of these driving trains is separately controlled by the levers 73 and 74, Fig. 2.

The described levers 73 and 74 are preferably each provided with toothed positioning segments so that they may be secured at different adjustments respecting speed of rotation. When travelling over straightaway courses, these levers will be similarly positioned thus imparting identical rates of speed through their gear reduction units 65 and 66 to the treads 22 and 23. When, however, the roadway enters upon a turn these speeds will be appropriately varied so that one or the other of the tractor treads runs faster by a suitable amount whereupon the subgrade machine may be made to follow the course of the roadway.

Power for the described propulsion and conveyor purposes is obtained from a single central driving engine 76 which may be gasoline or other fuel fed from a tank 70. A belt takeoff designated at 77 is shown in Fig. 2 to impart rotation to the transmission apparatus 72 for driving the conveyor as well as for driving the tractor elements.

This group of elements, shown in diminutive scale in Fig. 2, includes a driven pulley concealed from view by the right hand end of belt 77, a first stage speed reduction unit 70, partially concealed by platform 56, and a second stage reducer 80 which drives the differential transmission unit 72. The latter converts this rotary

power at optionally controllable rates of speed to the system of shafts 67 and 69.

The reference numeral 78 designates an electric generator which may be driven through a takeoff from the already described transmission system or if preferred it may be a self-contained fuel powered unit. Electrical power thus generated is required for operating the vibratory tamping instrumentalities 126 and 111 which will be described later. Access to various ones of the power, control, and servicing apparatus is easily had from the platform 56 and in close proximity to this position a control operator may also have access over a catwalk 79 to the scraper blade adjustment cranks 81. Accordingly, but one supervisory control operator is required to direct the subgrade planer throughout its course of travel, whether over straightaway or curved sections of the roadway. This includes giving the required attention to crowning the straightaway to assist drainage and to flatten the curves, where level conditions are usually preferred.

At the front of the channel member 36, as best revealed in Fig. 4, there are secured an appropriate number of guide brackets 82 with which there cooperate the guide bracket followers 83 best seen in Fig. 12. The stationary brackets 82 are shown to be secured to the forward flange of channel beam 36, but if preferred a separate beam to support these elements, may be provided, there being adequate space and clearance above the sub-frame channels 24 and 25 for this purpose. In this way perpendicular parallel motion is assured to the triangular brace structure 84 comprising vertical and horizontal components, Fig. 12, that may be welded to the inclined scraper blades 85 and 86. Blades 85 and 86 are symmetrical components which abut each other closely as at 87, and each blade has secured to it a slightly curved continuation section 88 and 89 which undergoes the actual scraper or planer engagement with the subgrade granular material.

The angle of inclination shown tends to gather the accumulated subgrade material into a mass which is continuously advanced as the machine travels forward. When the mass accumulations exceed the level of the blades 85 and 86, any excess works its way up the blades as a ramp and spills over into the channel receptacle 36. Between the blade sections 85 and 86 there is provided a threaded coupling member 91 which is pivotally articulated to both blades. By rotating the central one of the three adjustment cranks 81, Fig. 2, which is secured to shaft 92, Fig. 1, the coupling member 91 may be raised or lowered thereby imparting corresponding adjustment to both of the adjacent ends of the blades 85 and 86.

This so-called coupling member 91 is essentially a link having pivoted articulation with both of the blade sections 85 and 86, as best shown in Fig. 12. In addition, member 91 includes an intermediate portion which is vertically bored and threaded to have screw engagement with adjustment shaft 92, see also Fig. 1. This provision is made in order to assure that the two blade sections 85 and 86 remain substantially at the same level at their juncture.

The endmost adjustment screws 93 and 94, Fig. 1, see also Fig. 4, terminate with ball extremities 95 that reside in the socket fixtures 96 so that adjustment of these endmost screws 93 and 94 vary the elevation of the remote ends of the blades 85 and 86. This permits the introduction of some variation by which crowning of the road may be achieved where desired, namely, on straightaways and leveling of where desired usually on curves.

Shield plates 100, Fig. 11, secured to the inner surfaces of the forwardly extending portions of the tractor side frames, abut the ends of the blade assembly 85-86, boxing in the gravel or other fill material accumulations and confining such to overspilling solely in the direction

backwards, over the blade inclination and onto the conveyor channel 36.

At the front end of each tractor tread assembly as best observed from Figs. 2 and 3 there is provided a cantilever framework support, generally designated 101 and 102, see also Fig. 11. This consists of a pair of horizontal beam members 103 rigidly integrated with its framework substructure by means of the struts 104 and carrying at their foremost ends journals 105 for a rock shaft 110 with which is integrated a crank arm 106. When a control arm 107, also fast to the shaft 110, is permitted to assume the position shown in Fig. 3, arm 105 may hang downwardly disposing the support links 108 of a frame 109 in such a manner that the tamping plate 111 comes into engagement with the ground surface of the roadway side strips thereat, whereupon the vibratory elements 112 which may be powered electrically by the generator 78, perform a settling or stabilizing of the partially prepared flanking strip area before they are encountered by the treads 22 or 23. This prevents irregularities of movement which might otherwise be transmitted to the entire machine due to the delayed settling of crushed rock or other material fragments after they have been encountered by the tractor treads.

It is to be observed that the scraper which is comprised of two half sections 85 and 86 each having curved continuations 88 and 89 possesses a significant slope. Also, at the outermost ends of the scraper assembly, confinement of the fill material accumulations is aided by the provision thereat of the perpendicular shield plates 100, Figs. 1, 4 and 11, secured to the tractor side frame structures so as to prevent any of the accumulations from spilling into the region of the tractor treads. Upon encounter with the subgrade material which is usually crushed rock, gravel or similar substance, the effect will be to carry along an accumulation of subgrade material excesses, filling in holes or voids whenever they are encountered and scraping away excesses to add to the accumulations. By skill which is acquired from practice, the deposition of crushed rock or other subgrade fill material may be controlled so that the excess accumulations are marginal and waste through over supply is at a minimum.

Whenever these accumulations rise above the upper limit of the scraper blades 85 and 86 they spill over into the channel 36 whence they are directly carried away to one side or the other of the roadway by the conveyor paddles 49.

The level of the roadway after having been traversed by the template or scraper blades 85—86 may in this way be regulated to a precise condition determined in correspondence with the pre-leveled side shoulders or strips 37.

The entire unit may be driven from a single power source 76, as already described, which comprises a fuel engine whose rotary power output is transmitted by belt 77 to a speed reduction and transmission unit 70. The latter includes a rotary drive shaft continuation to a further reducer 80, that in turn leads to the lever controlled transmission 72, and a sidewise take-off that drives another shaft 90' Fig. 1. Shaft 90' imparts rotation to an alternatively clutch-coupled member 90 which powers shaft system 54 or shaft system 57 in accordance with the setting of lever 59.

To stabilize the leveled roadway novel means will now be described which makes unnecessary the heretofore known practice of rolling.

At the rear of the machine as best viewed in Figs. 2 and 3 there may be observed a transversely extending rock shaft 121 which is rotatably supported by a series of arms 122 from the principal beam 21, also see Figs. 8 and 9. When the rock shaft 121 is disposed in its active position, a series of arms 123 carried thereby, each having a threaded nut 124, engaged by an adjustable and

threaded support shaft 125, permits the weighted tamping plates 126 to come into engagement with the subgrade surface. The vibratory electrically driven motor elements 127, Fig. 5 thereof, produce a tamping and settling effect akin to that heretofore produced by rolling operation. The several tamping plates 126 are contiguously disposed after the manner best indicated in Fig. 2. Between each adjacent pair, see also Figs. 6 and 7, there is provided a coupling bracket 128 which is pivotally articulated as at 129 to an individual rubber mount bracket 131. Thus, by rotating the adjustment screws 125 and raising the coupling brackets 128 the level at which the vibratory plates are disposed is blindingly regulated as between adjacent plates without interfering with the individual vibratory action imparted to each plate by its related motor 127.

From the foregoing it will be understood that by means of the described subgrade planer and stabilizer certain intermediate procedures involving added labor costs which are required in accordance with standard specification practice, lend themselves to be accomplished with but a single pass. Moreover, all of the processing operations are made without forms, rails or other factors heretofore constituting material expense in paving and road building operations.

With roadway preparing operations thus reduced in terms of labor unit expenditure, substantial savings may be effected which will be reflected in state and national highway construction programs and consequently should result in corresponding public tax reduction. In addition to financial considerations, the combining of what has heretofore been separate and detached steps into a single effort, will result in speedier completion of construction work so that more miles can be paved over a given period of time.

While the present invention has been expressed and described with reference to certain particularized examples, it will be understood nevertheless that various departures and variations are within the primary contemplation. Accordingly, for an understanding of the scope of this invention reference should be had to the accompanying claims without regard to the specific description and illustrations in the preceding explanation and drawings.

45 The invention claimed is:

1. In a subgrade fill planing machine, a principal frame having sufficient width for transversely spanning a roadway, a channel member forming a frontal transverse beam element of said principal frame and having its web flanges disposed upwardly, a plurality of perpendicular spaced guide brackets secured to the front of said channel member web flanges, an inclined planer blade comprised of a plurality of contiguous sections extending across the width of said principal frame, a triangular brace structure welded to the rear of each of said planer blade sections and comprising a horizontal component and a vertical component, guide bracket followers welded to the rear surface of said brace structure vertical components for confining its section to vertical motion in accordance with said guide brackets, coupling members for articulating adjacent edges of said planer blade sections, and means for adjusting the planer blade sections vertically within the range of movement afforded by said guide brackets and said coupling members which comprises a series of spaced vertically disposed threaded screw shafts, threaded nut portions extending from said principal frame with which said shafts threadably engage, and ball and socket articulation means between the ends of said shafts and aligned portions of said planer blade sections.

2. In a roadway processing machine, a main frame of width to span a roadway, a subframe at each side of and supporting said main frame, each said subframe being adapted to overlie the side strip flanking said roadway, an endless chain of tractor treads around each of said

subframes, a scraper secured to the forward end portion of said main frame for finely leveling fill material deposited on said roadway, and tamping means at the rear end portion of said main frame for stabilizing the fill material after it has been passed over by said scraper, said tamping means comprising a transverse rock shaft rotatably mounted in the rear of said main frame, a series of arms in radial alignment and spaced from each other secured to said rock shaft, a threaded nut element carried by each of said arms, a perpendicular shaft having threaded engagement with each of said nut elements for vertical adjustment and including at its lower end a support bracket coupling and rubber mounts, and a series of self powered vibratory tamping plates arranged in alignment with each of said bracket couplings connected to the abutting ends of adjacent ones of said tamping plates.

3. A machine for preparing roadway subgrade surfaces for pavement which comprises, a principal frame adapted to span the width of a proposed roadway, a subframe on each side of said principal frame adapted to overlie the side strips flanking on both sides of the proposed roadway, said subframes including portions which extend substantially beyond said principal frame at the front of the machine, a system of tractor cleats carried by each of said subframes for riding upon said side strips, a central power engine carried by said principal frame for driving said tractor cleat systems to thereby propel said machine, devices carried by said principal frame for scraping the subgrade material of said roadway surface as said machine is propelled, and a tool carried at the front end of each of said subframes for tamping the subgrade material disposed at said flanking strip regions on both sides of the roadway before they are encountered by their respective subframe tractor cleat systems, whereby the subgrade material of the flanking strip regions is compacted and stabilized to establish at each side strip a reference level from which the devices carried by the principal frame are gauged in respect to their roadway surface scraping operation.

4. The combination set forth in claim 3 in which said tool carried at the front end of each of said subframes comprises a tamping plate the width of each of the roadway flanking strips, and a power driven vibratory element imposed upon said tamping plate whereby to settle and stabilize the surface materials of said flanking strips so that they may not become dislodged or shifted when subsequently they are encountered by the subframe tractor cleat systems.

5. The combination set forth in claim 3 in which said devices carried by said principal frame for scraping the roadway surface comprises a roadway width spanning assembly of downwardly and forwardly inclined scraper blades for striking off roadway surface levels and providing ramp-like inclined surfaces over which struck off roadway surface materials may be carried, and a transversely arranged endless belt conveyor behind said scraper blade assembly extending beyond the flanking strips and said subframes, whereby the carried roadway surface materials may be discharged beyond the range of the flanking strips.

6. The combination set forth in claim 3 in which said

devices carried by said principal frame for scraping the roadway surface includes a foremost alignment of scraper blades for striking off a surface level and scraping away surface materials in excess of such level, and a rearmost alignment of tamping plates each bearing an individually driven vibratory element for settling and stabilizing the scraped roadway surface following the action of said scraper blades, adjacent ones of said tamping plates and borne vibratory elements being connected together by pivotally articulated coupling brackets.

7. The combination set forth in claim 3 in which said tool carried at the front end of each of said subframes comprises a cantilever structure carried by and extending forwardly of each subframe, a tamping element pendulously supported from each of said cantilever structures, and a vibratory element borne by each of said tamping elements for actuating said tamping elements upon the roadway flanking strips in front of each subframe and its system of tractor cleats to stabilize the surfaces thereof before they are encountered by the tractor cleats.

8. A machine for preparing roadway subgrade surfaces for pavement which comprises, a principal frame adapted to span the width of a proposed roadway, a subframe on each side of said principal frame adapted to overlie the side strips flanking on both sides of the proposed roadway, said subframes including portions which extend substantially beyond said principal frame at the front of the machine, a system of tractor cleats carried by each of said subframes for riding upon said side strips, a central power engine carried by said principal frame for driving said tractor cleat systems to thereby propel said machine, devices carried by said principal frame for scraping the subgrade material of said roadway surface as said machine is propelled, tamping devices carried between the subframes to the rear of said scraping devices for settling and stabilizing the subgrade material of the scraped roadway surface as said machine is propelled, and a tool carried at the front end of each of said subframes for tamping the subgrade material disposed at said flanking strip regions on both sides of the roadway before they are encountered by their respective subframe tractor cleat systems, whereby the subgrade material of the flanking strip regions is compacted and stabilized to establish at each side strip a reference level from which the devices carried by the principal frame are gauged in respect to their roadway surface scraping and tamping operations.
